T. C. TYRRELL.
PLATFORM FOR FREIGHT CARS.

No. 449,452.

Patented Mar. 31, 1891.

UNITED STATES PATENT OFFICE.

THOMAS C. TYRRELL, OF GLENDIVE, MONTANA.

PLATFORM FOR FREIGHT-CARS.

SPECIFICATION forming part of Letters Patent No. 449,452, dated March 31, 1891.

Application filed July 22, 1890. Serial No. 359,477. (No model.)

To all whom it may concern:

Be it known that I, THOMAS C. TYRRELL, of Glendive, in the county of Dawson and State of Montana, have invented a new and Improved Platform for Freight-Cars, of which the following is a full, clear, and exact description.

The object of the invention is to provide a new and improved platform specially designed for freight-cars and adapted to close the space between the ends of the adjoining cars in the train, to prevent brakemen from falling between the cars when passing from one car to the other.

15 The invention consists of a platform pivoted to the end of a car and adapted to fold onto the car end or extend horizontally therefrom.

The invention also consists of certain parts and details and combinations of the same, as 20 will be hereinafter fully described, and then pointed out in the claims.

Reference is to be had to the accompanying drawings, forming a part of this specification, in which similar letters of reference indicate 25 corresponding parts in all the figures.

Figure 1 is a perspective view of the improvement as applied and in a folded position. Fig. 2 is a side elevation of the same in an extended position. Fig. 3 is an enlarged 30 plan view of one end of the platform, and Fig. 4 is a sectional side elevation of the same.

The improved platform A is secured to each end of the freight-car B and near the top of the latter, as is plainly shown in Figs. 1 and 35 2. Each platform A is provided with two side bars C and C', connected with each other by the transverse rods D, E, and F, of which the transverse rod D is mounted to turn in a number of screw-eyes G, secured to the timber of the car end.

40 The several rods D, E, and F are connected with each other at suitable intervals by strips H, supporting transversely-extending corrugated iron plates I, so as to form a net-work sufficiently close to prevent the brakeman's foot from passing between the meshes when stepping on the platform. In order to hold the several plates H apart, washers J are introduced between the same and preferably 45 held on the rod E, as is plainly shown in Fig. 1.

Near the ends of the rod E are pivoted two side bars K and K', connected with each other

5 at their outer ends by a transverse rod L, so as to form a pivoted extension on the platform A, which extension is free to swing upward when the platform is extended and the two cars come close together. In order to hold 55 this extension in horizontal position on the main platform, the inner ends of the said bars K and K' are each provided with a shoulder K², (see Figs. 3 and 4,) which shoulder is adapted to engage the under side of the transverse rod F, so that when the platform is held in a horizontal position the extension is in the same position, but is free to swing upward. 65 The said bars K and K' are also connected with each other between the rods E and L with a corrugated plate K³, similar to the plates I, previously mentioned.

To the outside of the side beam C is pivoted 70 a link O, guided in a suitable keeper P, fastened to the side of the car B opposite the side containing the usual ladder by which brakemen can reach the top of the car or descend from the same. The link O is articulated and is pivotally connected with the upper end of a lever Q, fulcrumed at Q' on the side of the car B, and is guided in the keeper R, fastened to the side of the car. On the lower end of the lever Q is hinged a handle S, 80 which serves to conveniently move the lever Q so as to throw the platform A into a horizontal position, as shown in Fig. 2, or to throw the same against the end of the car, as is plainly illustrated in Fig. 1. 85

The handle S is adapted to be locked in its two extreme positions in recesses formed by bent flanges T and T', formed on a bar T², secured to the side of the car. When the handle S is moved under the flange T, it may be 90 locked in place by a cam-lever U, fulcrumed on the right-hand end of the bar T². When the cam-lever U is thrown out of contact with the edge of the handle S, the latter can be moved from under the flange T, so as to shift the 95 lever Q into its left position, as is shown in Fig. 1. The handle S is then passed under the flange T', and locked therein by a cam-lever U', similar to the cam-lever U, and fulcrumed on the left-hand end of the bar T². 100 When the handle S engages the flange T', the platform extends in a horizontal position, as is plainly shown in Fig. 2, and when the handle S is locked under the flange T' the plat-

form A is folded onto the end of the car. When the train is in motion, the lever Q is in the position shown in Fig. 2, and is locked in this position by its handle S engaging the flange T, with the cam-lever U locking the handle under the flange. The platform extends now in or about in a horizontal position, so that a brakeman when stepping from one car to another and missing his footing falls onto the platforms A, without any danger whatever of falling between the cars to the track to be injured.

When the train is not in motion and the platform not needed, the lever Q is shifted, as previously described, so that the platform folds against the end of the car, as is plainly shown in Fig. 1.

Having thus fully described my invention, I claim as new and desire to secure by Letters Patent—

1. The combination, with a platform pivoted to the end of the car, of a link pivotally connected with one side of the said platform, a lever pivoted to the side of the car and connected with the said link, and a locking mechanism, substantially as described, for locking the said lever in position when the platform is extended or folded onto the end of the car, substantially as set forth.

2. The combination, with a platform pivoted to the end of the freight-car, of a link pivotally connected with one side of the said platform, a lever fulcrumed on one side of the car and connected with the said link, a handle hinged on the said lever, and two locks adapted to alternately engage the said handle to lock the said lever in position when the platform extends horizontally or is folded

onto the end of the car, substantially as shown and described.

3. The combination, with a platform pivoted to the end of the freight-car, of an extension pivoted to the end of the said platform and extending in line with the same and adapted to swing upward, substantially as shown and described.

4. A platform for cars, comprising side bars, transverse rods connecting the side bars together, plates connecting the rods together, and strips on the said plates, substantially as described.

5. A platform for cars, comprising side bars, transverse rods connecting the side bars together, plates connected to the rods, and corrugated strips on the said plates, substantially as described.

6. A platform for cars, consisting of side bars, transverse rods connecting the side bars together, plates connecting the rods together, strips on the plates, and auxiliary side bars pivoted to one of the transverse rods and connected together by rods and a plate, substantially as herein shown and described.

7. The combination, with a platform pivoted to the end of a car, of a jointed link pivoted to the platform, a hinged and pivoted lever pivoted to the link, a bar provided with flanges to receive the lever, and pivoted cam-levers for locking the lever in the flanges of the bar, substantially as herein shown and described.
